INVENTOR.

Edward H. OTTO.

BY

Thomas J. Connolly

ATTORNEY.

UNITED STATES PATENT OFFICE

EDWARD H. OTTO, OF DETROIT, MICHIGAN

BAKE OVEN

Application filed April 22, 1929. Serial No. 356,967.

My invention relates to a new and useful improvement in a bake oven and has for its object the provision of an oven with a maximum capacity and a minimum fire space or 5 combustion chamber.

It is another object of the present invention to provide a bake oven of a single furnace type or of a type having a single fire box of sufficient capacity to accomplish what is ordinarily accomplished by the one furnace type of bake oven having a double set of fire boxes.

It is another object of the present invention to provide a bake oven of this class in which 15 a minimum grate surface will be required, a saving of fuel effected and a minimum amount of time and labor required for firing.

Another object of the invention is the provision of a bake oven of this class in which 20 the loss of heat on account of radiation through the walls may be reduced to a minimum.

Another object of the invention is the provision of an oven of large capacity having a 25 single damper mechanism.

Another object of the invention is the provision of a bake oven of the one furnace tunnel construction whereby the temperature of the oven may be raised to the proper degree in a minimum amount of time and whereby the heating effects desired through the operation of the dampers may be accomplished most quickly.

Other objects will appear hereinafter.

The invention consists in the combination and arrangement of parts hereinafter described and claimed.

The invention will be best understood by reference to the accompanying drawings which form a part of this specification and in which,

Fig. 1 is a front elevational view of the invention.

Fig. 2 is a sectional view taken on line 2—2 of Fig. 1.

Fig. 3 is a sectional view taken on line 3—3 of Fig. 1.

Fig. 4 is a sectional view taken on line 4—4 of Fig. 1.

Fig. 5 is a sectional view taken on line 5—5 of Fig. 1.

Fig. 6 is a sectional view taken on line 6—6 of Fig. 1.

Fig. 7 is a view similar to Fig. 2 showing 55 a modified form of the invention.

Fig. 8 is a view taken on line 8—8 of Fig. 7.

The invention comprises a front wall 11,

a rear wall 12 and side walls 13 and 14 which

are preferably formed from brick. A layer 60

16 of insulation is positioned between the outer walls and the inner wall 17 which is

also formed from brick. Projecting rearwardly from the front wall are bridge walls

or baffles 18 and 19 which extend parallel

and in spaced relation to the forwardly ex-

tending bridge walls or baffles 20 which pro-

ject inwardly from the rear wall 12 and serve

to form the fire box. A passage 21 is formed

between the bridge walls 19 and 20 and a 70

passage 22 is formed between the bridge wall

19 and the inner wall of the side wall 14. A

passage 23 is formed between the bridge wall

18 and the inner portion of the side wall 13

and a passage 24 is formed between the bridge 75

wall 18 and the adjacent bridge wall 20.

An opening 25 is formed in the rear wall 12

and closed by the doors 26 and 27, these doors

affording communication to the fire box in

which is positioned the grate 28. Projecting 80

rearwardly centrally of the front wall 11 is

a tapered projection 29 which serves as a

divider for dividing the gases and direct-

ing them on opposite sides thereof, the gases

travelling in the direction indicated by the 85

arrows in Fig. 2. Clean-out openings 30 are

formed in the walls 11 and 12, these clean-out

openings being closed at their inner ends by

suitable fire bricks or fire clay. A door 31

serves as a closure for the oven 32, the base 90

of which is lined with suitable lining 34 po-

sitioned on the bridge 33.

As shown in Fig. 6, the gases travel from

the fire box upwardly in the space 35 which

is determined by the front wall and the ver-

tically extending bridge 37, the damper 36

being positioned in the passage 35. These

gases then pass through the tubes 38 posi-

tioned in the oven 32 from whence they

emerge into the passage 39, these gases hav-

100

ing access to the passage 35 only after traveling around the bridge walls 18 and 19. The passage 39 may be termed a soot collector as most of the soot in the gases will be deposited on the base 39' of the passage 39. The gases then pass along the inclined horizontally directed passage 40 from whence they issue into the outlet flue 41 at the end of which is positioned a deflecting bridge 42. This deflecting portion 42 prevents a mingling of the gases approaching the end of the flue from opposite sides and also prevents a back-draft when the fire dies down. A damper 43 is mounted in the end of the outlet flue 41 to control the flow of gases therethrough. A stem 44 is mounted on the damper 43 and provided with teeth so as to form a rack bar which meshes with the pinion 45 which may be rotated by rotation of the pulley 46 on which are secured the chains 47 which extend to a position easily accessible to the operator.

The baffling of the gases and directing of the same into the passages indicated and through the pipe as located, permits the construction of the furnace in such a manner that a single firing box will suffice. The damper regulation also accomplishes a quick variation of temperature in the oven.

In the modified form shown in Figs. 7 and 8 a baffle wall 50 is mounted to project upwardly from the base, this baffle wall cooperating with the bridge wall 49 which is located at opposite sides of the grate 28' which is accessible through the doors 26' and 27'. The flue in this form of construction is at the lower side of the furnace instead of the forward side. The gases pass into the passage 51 whence they are directed into the passage 39' and through the tubes 38' thence through the passage 52 into the outlet flue 53. The remaining features of the structure as described for the preferred form are present in this modified form and the advantages sought for in the preferred form are obtained in the modified form but for simplicity of structure and a maximum economy in operation, I prefer to use the structure shown in the modified form.

While I have illustrated and described the preferred form of my invention, I do not wish to limit myself to the precise details of structure shown but desire to avail myself of such variations and modifications as come within the scope of the appended claim.

Having thus described my invention, what I claim as new and desire to secure by Letters Patent is:

In a bake oven, a furnace construction, comprising: side walls, a front and rear wall, a top and a bottom; a grate located at substantially the medial line of said structure adjacent its bottom and accessible through the rear wall thereof; bridge walls projecting inwardly at opposite sides of said grate in par-

allel spaced relation and parallel to the side walls, said bridge walls terminating rearwardly of said front wall; baffle walls projecting inwardly from said front wall and extending between said bridge walls and the side walls; an oven compartment positioned above said furnace construction; a plurality of tubes projected through said oven compartment adjacent the upper side thereof and terminating with their ends in spaced relation to said front and rear walls, the front ends of said tubes communicating through a passage with the space between said side walls and said baffle walls, and the rear end of said tubes communicating through a passage with a chamber extending above said oven compartment, said chamber communicating adjacent its forward side with an outlet flue, the rear ends of said tubes being elevated relatively to the base of said last mentioned passage; a deflecting member projecting slightly inwardly of said flue at one end; and a damper for opening and closing said end.

In testimony whereof I have signed the foregoing specification.

EDWARD H. OTTO.
